SIGNAL GENERATION SYSTEM

Conrad H. Hoeppner, Washington, D. C.

Application November 14, 1946, Serial No. 709,857

5 Claims. (Cl. 332—9)

(Granted under the act of March 3, 1883, as
amended April 30, 1928; 370 O. G. 757)

1

This invention relates to signal generating systems and in particular to generator systems for producing multiple pulse signal groups in which the individual signals are controlled in time occurrence in accordance with intelligence quantities.

In numerous applications of intelligence transmission apparatus it is desired to transmit information relative to a plurality of variable quantities via a single communication link. Where intermittent response to each of the variable quantities is satisfactory, time sharing operation such as that described in the copending application Serial Number 709,629 filed November 13, 1946, titled "Pulse multiplex system" of C. H. Hoeppner may be employed. An intelligence modulator is required in such apparatus to transform the variable quantities into a time sharing form which may be conveniently transmitted by a single link.

It is therefore an object of the present invention to provide a modulator system for producing a time sharing signal containing information relative to a plurality of variable quantities.

Another object of the present invention is to provide a modulator system of simple structure for producing a series of pulse signals in which individual pulses of the series are separated in time from preceding pulses of a reference series of pulses in accordance with intelligence quantities which it is desired to transmit.

Other and further objects and features of the present invention will become apparent upon a careful consideration of the accompanying drawing and following detailed description.

The single figure of the drawing is a schematic diagram, partly in block, of a preferred embodiment of the features of the present invention.

In accordance with the general concepts of the present invention, a signal generation system is provided which is capable of producing intelligence containing multiple signal groups. The system is of a simple nature permitting space, weight, and power economies heretofore unobtainable. Operation of the system is accurately controlled in time by a stable timing device. Signals produced by the timing device are applied to gas filled electron tubes, all of which are normally non-conductive and may if desired be ionically heated with consequent low power requirements. In response to a first one of the timing signals a first one of the gas tubes is brought to conduction for a brief instant of time to produce a signal varying substantially linearly with time. The varying signal is supplied to a second gas tube which will be brought to conduction a selected interval of time after the start of the varying signal in dependency on a first intelligence quantity. Subsequently, a third gas tube will be brought to conduction as a result of the action of the first tube to produce a second signal varying substantially linearly with time to permit the operation of a fourth electron tube in time dependency on a second intelligence quantity. It is therefore possible to produce signals relative to a plurality of quantities by employing an appropriate number of electron tubes. Where all of the signals thus produced are to be transmitted via a single channel, they may be combined in a conventional manner.

With particular reference to the figure, a typical intelligence modulation system is shown which may be timed in operation by a sinusoidal oscillation signal generator 10. From these sinusoidal signals, a series of pulse type signals of short duration are derived by the pulse former 11. Short duration impulses thus produced are applied in parallel to grids 12, 13, 14 of gas filled primary electron tubes 15, 16, 17. The electron tubes 15, 16, 17 are preferably of the tetrode variety in which the initiation of the conductive condition is dependent upon the voltages applied to two control elements or grids. In the steady state, tubes 15, 16 and 17 are non-conductive and hence do not require anode circuit power. This non-conductive condition is maintained by a negative voltage supplied to the grids 12, 13, 14 from terminal 18 and in operation when tubes 15, 16 and 17 may be periodically conductive is aided by an average voltage developed across the cathode resistances 19, 20, 21. In addition, bias is applied to grids 22, 23, and 24 from terminal 25. The bias voltages supplied to terminals 18 and 25 are of sufficient magnitude so that either, alone, can prevent conduction within the tubes 15, 16, 17. In other words, positive signals must be simultaneously supplied to the two grids of each tube to initiate conduction therein. Also a sufficient voltage differential must be present between anode and cathode to sustain conduction. Disposed in the anode circuit of each of the primary tubes 15, 16, 17 is a time constant circuit typified in the case of tube 15 by the resistance 26 and capacitance 27. This time constant circuit serves to limit the duration of the conductive condition within tube 15. In the cathode circuit of each primary tube is a time constant circuit typified for tube 15 by the resistance capacitance combination 19, 28. Conduction by tube 15 produces a charging of capacitance 28 so that a substantially linearly rising voltage is

obtained at the cathode of tube 15. This rising cathode voltage aids the resistance-capacitance circuit 26-27 in the job of extinguishing tube 15 and helps to hold tube 15 non-responsive to signals supplied to the grids thereof during an interval of time following the initiation of conduction therein.

The varying signal from the cathode of tube 15 is supplied to the grid 29 of a triode type gaseous secondary electron tube 30 which is normally maintained non-conductive by virtue of a negative biasing voltage supplied across terminals 31. The rising signal applied to grid 29 is in opposition to the average biasing voltage from terminals 31. The exact point in the cycle of rising grid voltage at which tube 30 becomes conductive may be and is varied at will by adjusting the position of the tap on the potentiometer 32 or by varying the magnitude of the voltage impressed between terminals 31. By this means then, it is possible to control the time displacement between the initiation of conduction in tubes 15 and 30 in accordance with the position of a shaft, as by the movable contact on potentiometer 32, or by a varying voltage signal applied to terminals 31.

Termination of conduction in tube 30 is provided by the resistance-capacitance network 33-34 placed in the anode circuit thereof. Conduction by tube 30 removes more charge from capacitance 34 than can be supplied by resistance 33 so that the capacitance discharges, lowering the voltage impressed across the tube. Eventually this voltage falls to a level at which conduction by tube 30 cannot be maintained. Conduction then ceases and the tube becomes inoperative.

Upon the initiation of conduction in tube 30, a sharp voltage change occurs across the cathode resistance 35. This voltage change is applied through the coupling capacitance 36 to an output terminal 37. In certain applications it may be desirable to employ a small value of capacitance for element 36 to obtain a differentiating action.

The varying signal from the cathode of tube 15 is also supplied to the grid 23 of tube 16. The signals supplied to grid 13 are not of sufficient amplitude to, alone, cause the initiation of conduction in tube 16, however, when supplemented by the rising voltage from the cathode of tube 15 a pulse signal from former 11 can cause the initiation of conduction. Tube 16 may then be employed to permit the subsequent initiation of conduction in tube 38 in accordance with a signal obtained from potentiometer 39 and the initiation of conduction in tube 17 in accordance with a subsequent signal from pulse former 11.

Primary tube 17 operates in a manner similar to tubes 15 and 16, however, the changing voltage obtained at the cathode thereof is applied to the grid 22 of tube 15 through capacitance 40 and resistance 41 so that conduction by tube 15 can be initiated again by a subsequent pulse from former 11 to continue the operation of the primary tube chain.

It is apparent that any desired number of primary tubes may be inserted between the tubes 15 and 17 to control operation for any number of variable quantities. In such case a corresponding number of secondary tubes 30, 38, etc., would be required.

When the equipment is first turned on, the initiation of the conductive condition in tube 15 may be facilitated by a momentary reduction in

the biasing voltage for grid 22. Such bias reduction may be effected by a momentary grounding of the junction between resistance 41 and capacitance 40, as by switch 42, until the cyclic operation is started.

From the foregoing discussion it is apparent that considerable modification of the features of the present invention is possible and while the device here shown and described and the form of apparatus for the operation thereof constitutes a preferred embodiment of the invention it is to be understood that the present invention is not limited to this precise device and form of apparatus and that changes may be made therein without departing from the scope of the invention which is defined in the appended claims.

The invention described herein may be manufactured and used by or for the Government of the United States of America for governmental purposes without the payment of any royalties thereon or therefor.

What is claimed is:

1. A signal generator device for producing a series of intelligence conveying pulse type signals in which each of the signals is individually spaced from a preceding reference signal in accordance with intelligence to be conveyed, comprising; means producing a series of accurately spaced timing signals, individual primary gaseous electron tubes for each intelligence quantity to be conveyed, means interconnecting the primary electron tubes in a tandem manner so that one tube may be controlled in operation by a preceding tube of the tandem in accordance with the timing signals, enabling means permitting initiation of conduction in a primary electron tube for a first quantity in accordance with a first timing signal, individual secondary gaseous electron tube means for each intelligence quantity to be conveyed, separate integrator means connecting each of said secondary tubes to a corresponding primary tube, said last named means being operative to render each of said secondary tubes conductive in response to the establishment of conduction in the corresponding primary tube but time delayed therefrom, the time delay being in duration dependency on the corresponding intelligence quantity to be conveyed, a common output channel, and means delivering a signal into the common output channel in response to a change in conductivity conditions of the secondary electron tubes.

2. A signal generator device for producing a series of pulse type signals individually spaced from a preceding signal of a reference signal train in accordance with intelligence to be transmitted, comprising; means producing a series of accurately spaced timing signals, a first soft tube electron tube means responsive to a first reference signal of the train to cause the production of a first keying signal varying in amplitude substantially linearly with time over a portion thereof, a second soft tube electron tube means responsive to the first keying signal and a first intelligence quantity to change conductivity conditions in interval of time after the first timing signal in dependency on a first intelligence quantity, a third soft tube electron tube means responsive to a second timing signal of the train to produce a second keying signal having linear amplitude variation with time, a fourth soft tube electron tube means responsive to the second keying signal and to a second intelligence quantity to change conductivity conditions an inter-

val of time after the second timing signal in dependency on a second intelligence quantity, means deriving output signals in a fixed time relationship to the change in conductivity conditions of the second and fourth electron tubes, and additional electron tube means for producing additional output signals in accordance with additional intelligence quantities to be conveyed.

3. A signal generator device for producing a series of pulse type signals individually spaced from a preceding signal of a reference signal train in accordance with intelligence to be transmitted, comprising; means producing a series of accurately spaced timing signals, a first soft tube electron tube means responsive to a first timing signal to cause the production of a first keying signal varying in amplitude substantially linearly with time over a portion thereof, a second soft tube electron tube means responsive to the first keying signal and a first intelligence quantity to change conductivity conditions an interval of time after the first timing signal in dependency on the first intelligence quantity, a third soft tube electron tube means biased in part by the first electron tube means responsive to a second timing signal of the train to cause the production of a second keying signal having linear amplitude variation, a fourth soft tube electron tube means responsive to the second keying signal and a second intelligence quantity to change conductivity conditions an interval of time after the second timing signal in dependency on a second intelligence quantity, means deriving output signals in a fixed time relationship to the change in conductivity conditions of the second and fourth electron tubes, and additional electron tube means for producing additional output signals in accordance with additional intelligence quantities to be conveyed.

4. A signal generator device for producing a series of pulse type signals individually spaced from a preceding signal of a reference signal train in accordance with intelligence to be transmitted, comprising; means producing a series of accurately spaced timing signals, a first soft tube electron tube means responsive to a first timing signal of the train to produce a current surge and to cause the production of a first keying signal varying in amplitude substantially linearly with time over a portion thereof, a second soft tube electron tube means responsive to the first keying signal and a first intelligence quantity to change conductivity conditions an interval of time after the first reference signal in dependency on the first intelligence quantity, an energy storage circuit, a series resonant inductance-capacitance circuit connected to an electrode of the first electron tube to produce an enabling signal in response to the current surge produced thereby, a third soft tube electron tube means responsive to the enabling signal and to the timing signals to produce a third current surge when a second timing signal and the first positive crest of the enabling signal bear selected amplitude relationships, means producing a second keying signal having linear amplitude variation in re-

sponse to the third current surge, a fourth soft tube electron tube means responsive to the second keying signal and to a second intelligence quantity to change conductivity conditions an interval of time after the second timing signal in dependency on a second intelligence quantity, means deriving output signals in a fixed time relationship to the change in conductivity conditions of the second and fourth electron tubes, and additional electron tube means for producing additional output signals in accordance with additional intelligence quantities to be conveyed.

5. A signal generator device for producing a series of pulse type signals individually spaced from a preceding signal of a reference signal train in accordance with intelligence quantities to be transmitted, comprising; means producing a series of accurately spaced timing signals, a first soft tube electron tube means responsive to a first timing signal of the train to initiate a current surge and cause the production of a first keying signal varying in amplitude substantially linearly with time over a portion thereof, means terminating the current surge in the first tube after a predetermined duration thereof, a second soft tube electron tube means responsive to the first keying signal and a first intelligence quantity to initiate a second current surge an interval of time after the first timing signal in dependency on the first intelligence quantity, means terminating the current surge in the second tube after a predetermined duration thereof, an energy storage circuit connected to the cathode of the first electron tube to produce an enabling signal in response to the current surge produced thereby, a third soft tube electron tube means responsive to the enabling signal and to the timing signals to initiate a third current surge when a second timing signal and the enabling signal bear selected amplitude relationships, means terminating the third current surge after a predetermined duration thereof, means producing a second keying signal having linear amplitude variation in response to the third current surge, a fourth soft tube electron tube means responsive to a second keying signal and a second intelligence quantity to initiate a fourth current surge an interval of time after a second timing signal in dependency on a second intelligence quantity, means terminating the current surge in the fourth tube after a predetermined duration thereof, and additional electron tube means for producing additional output signals in accordance with additional intelligence quantities to be conveyed.
